UNITED STATES PATENT OFFICE.

ISIDOR KITSEE, OF PHILADELPHIA, PENNSYLVANIA.

COLOR-CARRIER FOR COLOR PHOTOGRAPHY.

1,221,457.

Specification of Letters Patent.

Patented Apr. 3, 1917.

Application filed September 13, 1916. Serial No. 119,905.

To all whom it may concern:

Be it known that I, ISIDOR KITSEE, a citizen of the United States, residing at Philadelphia, in the county of Philadelphia and State of Pennsylvania, have invented certain new and useful Improvements in Color-Carriers for Color Photography, of which the following is a specification.

My invention relates to an improvement 10 in color carriers for color photography.

Its object is to produce the color carriers in the most improved form.

In such processes, in which carriers for the colors are employed to produce the color 15 screen, it is of the utmost importance, that these carriers should be transparent and should be of desired dimensions, and not, as is so far the case, of dimensions differing for the different carriers, either in thickness or 20 otherwise.

For this purpose I have adapted the method as will be outlined in this application and claims following this application.

To illustrate some forms my invention 25 may take I have reference to the accompanying drawing.

In this drawing: Figure 1 is a plan view of a suitable base. Fig. 2 is a similar view of the base surfaced with a material, adapted 30 to be dissolved in an agent not injuriously affecting the film which will later on be placed on this material. Fig. 3 is a similar view of a suitable base, surfaced by the material as in Fig. 2 having placed thereon the 35 film out of which the carriers are to be fashioned. Fig. 4 is a similar view as Fig. 3 illustrating the divisions or cuts in the film. Fig. 5 is an enlarged portion of Fig. 4 and Fig. 6 is an enlarged portion of a blank, 40 adapted to be used for photographic purposes and afterward to be suitably sensitized and illustrating the color screen made of the divided film.

In these figures, 1 is the support, 2 the material surfacing the same, 3 the film, 4 indicates the cutting lines. In Fig. 5, 6 are the carriers fashioned out of the film, here shown by the process of cutting, 4 the cutting lines. In Fig. 6, 7 is the blank to be 50 later suitably sensitized and 8 its color screen as an entirety comprising here the three colors—blue-violet, green and red—and indicated by the numerals 9, 10 and 11 respectively.

55 It is supposed, that the film out of which the colored carriers are to be fashioned is

produced of a solution of dissolved cellulose, such for instance as celluloid. It is well known that celluloid is not soluble in water and will not be injuriously affected if placed 60 in contact with same. In this case the material 2, which surfaces the support 1, is therefore preferable, a solution of gum arabic, starch or similar substances, and as water has to penetrate and dissolve this 65 surfacing material, it is best that the support should consist of a stiff sheet or board of paper easily penetrable by water.

The method of producing the carriers in such instances is as follows:

A paper board is surfaced, with the aid of a brush or otherwise with a material adapted to be dissolved in water and as it is supposed that this material consists of a solution of gum arabic, then the support is provided with the surface of gum arabic and after the surface is dried out, a film of celluloid is produced thereon, by first dissolving the celluloid in its solvent, such for instance as amyl-acetate alone or intermixed with 75 acetone or other solvents.

Alcohol and ether, good solvents, have to be barred, as they leave the film in a translucent state when dry. Care has to be taken therefore to only employ such solvents as 85 will not affect the transparency of the dry film. The solution of celluloid may be applied to the layer of gum arabic with the aid of brush or otherwise.

Should the three color scheme be employed, three supports with their surfacing material and celluloid film have to be provided.

To produce the colors on the film, the celluloid solution may be colored and then three 95 different solutions be employed, one for the blue-violet, one for the green, and one for the red, if such colors are selected.

If it is desired, only one colorless celluloid solution may be employed and the films then, 100 after having been dried, colored to suit the requirements. One, as I said above, to represent the blue-violet, the second to represent the red and the third to represent the green.

With the aid of such machinery, as is used to-day, for the purpose of producing screens for half-tone photography, the film is then cut in squares of desired dimensions and I have found that it is an easy matter to make 110 these cuts every five hundredths of an inch and that it is even possible to produce cuts

eight hundredths of an inch, thereby producing individual pieces of the film small enough to require more than a half a million per square inch. After the film has 5 been cut, the support with its adhering film-pieces is soaked in water, whereby the gum arabic will be dissolved and the minute film-pieces will be released from their support and the adhering gum arabic. The different 10 colored film-pieces are then well intermixed and sprayed or otherwise placed on suitably prepared surfaces of the blank, later to be used for photographic purposes. The surface of this blank is best provided with 15 a slight coating of an agglutinant, so that these particles may adhere to the surface, but care should be taken that this agglutinant should be of proper consistency and should not be laid on too heavy, as otherwise 20 the particles will over-lay each other.

Great care should be taken in selecting the proper support. The same should be stiff enough so as not to bend during the process of cutting and hard enough so as 25 not to yield too much to the pressure of the cutting knife. Without the proper support it is impossible to produce good results.

I am well aware that the support itself 30 may consist of a material soluble in an agent not injuriously affecting the film proper, as for instance a solid block of glue, gelatin or similar substance which is soluble in water. In this case, the support or block 35 does naturally not have to be surfaced with an intermediate material. But I found, that such method is not very practical.

I am also aware, that the colors may be applied to the divided parts of the film and 40 not before, but such proceeding does not give good results.

Having now described my invention what I claim as new and desire to secure by Letters Patent is:—

45 1. In the process of producing color carriers for color photography the method which consists in securing a film out of which the carriers are to be produced onto a suitable base with the interposition of a 50 material soluble in an agent not injuriously affecting said film, dividing said film into a series of individual parts and freeing said parts from said support with an agent not injuriously affecting said parts.

55 2. In the process of producing color carriers for color photography the method which consists in surfacing a suitable support with a material soluble in an agent not injuriously affecting the material out of

which the color carriers are to be fashioned, securing to said material a film not soluble in the agent in which the surfacing material is soluble, coloring said film, dividing said film into a series of individual parts and freeing said parts from said support. 60 65

3. In the process of producing color carriers for color photography the method which consists in surfacing a suitable support with a material soluble in water, coating said surfacing material after being dried with a soluble cellulose in a manner so that said cellulose should produce a continuous film when dried, dividing said continuous film into required parts and freeing 75 said parts from said support. 70

4. In the process of producing color carriers for color photography the method which consists in coating a suitable support, surfaced with a suitable material, with a colored solution in which a soluble cellulose is dissolved, in a manner so that said coating should form a continuous film when dry, dividing said film into a series of individual parts and removing said parts from 80 85 said support.

5. As a new article of manufacture a support, a coating for said support, a celluloid film on said coating, said celluloid film divided into a number of individual parts. 90

6. A color carrier for color photography comprising a suitable colored and minute part of a celluloid film.

7. The method of producing color carriers for color photography which consists in securing a thin film of dissolved cellulose on a suitable support, with the interposition of a material soluble in a suitable agent, dividing said film into a series of individual parts during the time that 100 said film is adhering to said support, said individual parts colored to suit the requirements. 95

8. In the production of color carriers for color photography the steps which consist 105 in securing a film out of which the carriers are to be fashioned onto a suitable support, dividing then said film into a number of individual parts and freeing then said parts from said support with an agent not injuriously affecting said film. 110

In testimony whereof I affix my signature in the presence of two witnesses.
